POST FOR WALLS

Simon W. Oppenhuizen and Gordon Jack Cooper, Grand Rapids, Mich., assignors, by mesne assignments, to Westinghouse Electric Corporation, a corporation of Pennsylvania

Filed Oct. 16, 1959, Ser. No. 846,848
3 Claims. (Cl. 189—41)

This invention relates to a structural beam assembly 10 and more particularly to a structural beam used in the formation of partitions.

There is a growing need for structural members which can be used to assemble readily a partition wall and that can be readily disassembled to allow moving of the partition. This is particularly true with the modern office building and also applies to the modern home. Such structural members must not only be versatile as to assembly and disassembly but must also have a neat appearance and provide a partition capable of standing permanently.

The structural beam disclosed herein is designed to meet all of the above requirements and is adapted for use with a partition or wall formed from panels. It is, therefore, an object of this invention to disclose a structural beam used in the construction of panel type partitions.

It is a further object of this invention to disclose a structural beam which is adjustable to variations in the panel thickness.

Still another object of this invention is a structural beam which is a severable two piece unit having one piece or column which can be erected as a panel stop and locator before installation of the second or locking section.

A further object is to disclose a structural beam for use with partitions which can be erected without the use of special tools.

A still further object of this invention is to disclose a structural beam which covers minor damages that may occur to the edges of the panels.

Another object is to disclose a structural beam which is separable, having means which conceal the fact that fasteners are used to join the separable members together.

A still further object of this invention is to disclose a structural beam which is adaptable to be used for supporting partition and curtain wall panels of various types and characteristics.

These and other objects and advantages in the practice of this invention will be more apparent in the illustration and description of a working embodiment of the invention as hereinafter set forth.

In the drawings:

FIG. 1 is a fragmentary perspective view of the structural beam assembly;

FIG. 2 is a perspective view of the structural beam assembly being used to support a glass panel;

FIG. 3 is a perspective view of the floor anchor for the structural beam;

FIG. 4 is a plan view of the structural beam assembly with a door jamb attached to it.

The structural beam assembly 10 consists of separable column members 11 and 12 which are secured together by fasteners 15 and nuts 16. The structural beam 10 is anchored into position by an anchor assembly such as 60 (FIG. 3). The columns 11 and 12 are adapted to position, support and, in effect, join together the side edges of panels such as 13 and 13a.

Referring specifically to FIG. 1, the structural beam assembly is designated generally as 10. The structural beam assembly 10 is composed of separable columns 11 and 12, normally aluminum extrusions.

The column 11 is an elongated member being generally

2

H-shaped in cross sectional configuration and having a first leg 21 and a second leg 22 which are tied together at their approximate geometric centers by a cross tie 23. The cross tie 23 has a ferrule 28 formed therein. The ferrule 28 of the cross tie 23 has apertures 59 positioned at equally spaced intervals throughout the length of the column 11.

The ferrule 28 in the cross tie 23 also provides a channel for countersinking the heads of the fasteners 15, making them flush with the surface of the cross tie 23.

Secured to each of the legs 21 and 22, respectively, are first and second flange faces 24 and 25. The flange faces 24 and 25 extend transversely or normally both outwardly and inwardly from the legs 21 and 22. The outward extension is approximately four times that of the inward extension. The inward extensions of flange faces 24 and 25 cooperate with the cross tie 23 and portions of legs 21 and 22 to form a channel 29 for purposes hereinafter to be described.

The exterior surface of flange 24 is finished to provide a pleasing appearance to the member. The opposite surface is provided with an undercut keyway 26, of which flange 24 extends outwardly from the leg 21 for purposes hereinafter to be described.

The flange 25 is finished in a similar manner, an undercut keyway 27 also appearing in the opposite surface of flange 25.

The column 12 is positioned directly opposite the column 11 and is aligned therewith. The column 12 is also an elongated member having a generally H-shaped cross section configuration. It has a first offset leg 31 and a second offset leg 32. The offset legs 31 and 32 are tied together at their approximate geometric centers by cross tie 35. Offset legs 31 and 32 are offset inwardly or toward each other, a dimension equal to the thickness of legs 21 and 22 of column 11. This allows the offset portion of legs 31 and 32 to fit telescopically between legs 21 and 22. When columns 11 and 12 are telescopically interfitted, they offer a flush surface to the edges of panels 13 and 13a due to the fact that legs 31 and 32 are offset the thickness of legs 21 and 22.

Flanges 33 and 34 are secured to the respective offset legs 31 and 32. The flanges 33 and 34 are disposed transversely or normally with respect to the legs 31 and 32, extending both inwardly and outwardly with respect thereto. The outward extensions are approximately four times that of the inward extensions. The inward extensions of the flanges in combination with the cross tie 35 and portions of legs 31 and 32 together form a channel 30 for purposes hereinafter to be described. The flange 33 has a finished surface which is presented to the viewer and an opposite surface which contains an undercut keyway 39, the purpose of which will be explained hereinafter. Likewise, flange 34 has a finished surface and an opposite surface containing an undercut keyway 38, in the outwardly projecting portion of the flange.

The ends of the offset legs 31 and 32, opposite the ends having the flanges 33 and 34, are provided with inwardly extending ribs 36 and 37. The ribs 36 and 37 are spaced apart a sufficient distance to allow the narrow dimension of a rectangular nut 16 to pass therebetween. The purpose of the ribs 36 and 37 is to act as a stop means for the nut 16. The nut 16 is passed through the space between the ribs 36 and 37 widthwise and rotated, making the greater dimension of the nut 16 assume a crosswise position with respect to the ribs. The length of the nut is such that the ribs will limit its rotation. Thereafter, the ribs act as stop members, preventing the withdrawal of the nut 16. Thus, when a fastener 15 is inserted through the aperture 59 in ferrule 28, and a nut 16 threaded thereupon is passed widthwise between the ribs 36 and 37, turning of the fastener 15 will cause the nut

to assume a crosswise position and the columns 11 and 12 can be drawn into telescoping relationship.

The channel 30 formed between the cross tie 35 and the inwardly disposed extensions of flanges 33 and 34 is provided with an insert or feature strip 14, as shown in FIG. 1. In column 11, the channel 29 formed between cross tie 23 and the inward extensions of flanges 24 and 25 is also provided with a feature strip or insert (not shown). These inserts cover the heads of the fasteners 15 in column 11 and the metal in column 12, and present an attractive and neat appearance to the viewer. Also, different colored strips can be inserted in the channel for different decorative effects.

The structural beam assembly 10 is anchored into position by structural beam anchor assembly 60, best shown in FIG. 3.

The anchor assembly 60 is generally U-shaped and has aligned oppositely disposed rectangularly shaped backing plates 61 and 62 which are tied together at the bottom by web 63. A threaded fastener, such as 64, is anchored to the floor, ceiling or to some member to which it is desirable to secure the structural beam. The threaded fastener extends through a centrally located aperture in the web 63 and through a clamping plate 65 which is positioned between the plates 61 and 62, and atop the web 63. A nut 68 is then used to secure the structural beam anchor assembly 60 in position.

T-shaped stabilizer blocks 66 and 67 are secured to the plates 61 and 62, respectively, by some well-known means. The stabilizer blocks 66 and 67 are in alignment with each other and disposed on the opposite inside faces of the anchor assembly plates 61 and 62. The stabilizer blocks 66 and 67 are dimensioned so that the channels 29 and 30 formed in columns 11 and 12, respectively, will slide over the stabilizer blocks 66 and 67 and be locked in position thereby.

FIG. 3 shows the web member 63 as a solid member. However, within the broader scope of this invention, the member 63 can be made adjustable to correspond with the telescoping adjustment of columns 11 and 12 of the structural beam.

FIG. 2 shows the structural beam assembly 10 supporting a transversely disposed beam 53. The beam 53 may be secured to the structural beam assembly 10 by providing the end of the beam 53 with a projection bearing keys (not shown) which will engage the keyways 27 and 38 in columns 11 and 12, respectively.

The beam 53 is generally U-shaped and has longitudinally extending parallel spaced undercut keyways 54 and 55 formed in the bottom surface thereof. A land 56 remains on the bottom of the beam 53 between the parallel spaced keyways 54 and 55.

A generally U-shaped plate 41 bears keys 42 and 43 which engage the keyways 27 and 38, respectively, of columns 11 and 12. The structural panel 41 is dimensioned so that the outer surface thereof appears flush with the edges of outwardly extending flanges 25 and 34. The outer surface of the structural panel 41 is provided with parallel spaced longitudinally extending undercut keyways 44 and 45. A land 46 remains on the bottom of the structural panel 41 between the keyways 44 and 45.

A partition member 47, such as a piece of glass, abuts against the land 46 and is carried by the land 56.

Blind stop strips, such as 48, 51 and 52, engage the respective keyways 45, 54 and 55, holding the partition member 47 in position. The strips contain fingers 49 and 50, such as shown on the clip 52 (FIG. 2). The fingers 49 and 50 flare outwardly in opposite directions and snap into the undercut of the keyway, such as 50. Thus, it can be seen that strips such as 51 and 52 disposed in the keyways 54 and 55, respectively, will sandwich the partition 47 and maintain it in position on the land 56.

The blind stop strips such as 48, 51 and 52 are generally rectangular in shape and have a shoulder 57 which extends inwardly as shown on stop 52. The finger 50

flares outwardly from the shoulder 57 to engage the key 55. The blind stop strips are somewhat resilient due to their open construction. The resiliency of the blind strip in combination with the shoulder provides an important feature in that the strips can be used to clamp into position materials such as 47 varying in thickness from $\frac{1}{8}$ " to $\frac{3}{16}$ " of an inch. To position and clamp the thicker materials the strips 48, 51 and 52 are positioned as shown in FIG. 2. However, to position and clamp the thinner material the strips are reversed to their FIG. 2 position so that finger 50 of strip 52 will occupy the position that finger 49 now has. This causes the shoulder 57 to extend over the land 56 and reduce the effective width thereof. The strip 51 can also remain in the FIG. 2 position to accept material of intermediate thickness. The resiliency of the strips themselves will adjust for small variations in thickness.

FIG. 4 shows a means whereby the structural beam assembly 10 can be adapted to support a door jamb generally 80.

The door jamb is generally a U-shaped member having a bottom 85 and transversely extending offset arms 81 and 82. The offset portions of arms 81 and 82 are provided with keys 83 and 84, respectively. The keys 83 and 84 engage the keyways 38 and 27, respectively, of the columns 12 and 11. The arms 81 and 82 are offset a dimension which corresponds with the thickness dimension of flanges 34 and 25. Thus, a portion of the arms 81 and 82 will appear flush with the faces of flanges 34 and 35.

The offset leg 82 is extended beyond the bottom 85 of the jamb 80 and forms an abutment 86. The abutment 86 has an undercut longitudinally extending keyway 87 formed therein. The keyway 87 is adapted to receive a stop strip 88 which has a flared portion adapted to snap into the keyway 87. The stop strip 88 can be made of a resilient material, such as rubber, and used to cushion and seal a door, such as 89.

Assembly

It is to be understood that the columns 11 and 12 of the structural beam assembly 10 can be cut to any desired length for use with a partition that will extend only a fraction of the distance between the floor and ceiling, or which may extend the full distance between the floor and ceiling. Likewise, the components used with the structural beam assembly 10, shown in FIGS. 2 and 4, can be cut to any length necessary to meet the need.

For illustrative purposes, we will assume that a partition is to be assembled which will extend half-way between the floor and ceiling, since essentially the same assembly procedure would be used for any type of partition.

A partition line is laid out on the floor and fasteners, such as 64, are placed along the line at intervals determined by the width of the panels being used. Structural beam anchor assemblies, such as 60, are then fitted onto the fasteners 64 and secured into position by means such as nuts 68. It is to be understood that the structural beam anchor assemblies 60 could also be secured to the floor by means such as a lag screw, or any other suitable means.

When the structural beam anchor assemblies are in position, a column 12 of the desired length, this length usually being the height of the panel, is seated over the stabilizer block 66. The channel 30 formed therein engages the T-shaped stabilizer block 66 and locks the column 12 into position.

Panels 13 and 13a are then positioned so that they abut the flanges 33 and 34 and also abut against the offset legs 31 and 32.

Fasteners 15 are then placed in apertures 59 of column 11 and nuts 16 are started on the fasteners. The nuts 16 are positioned so that the width dimension thereof will pass between the ribs 36 and 37 on column 12. The column 11 is then placed in telescoping position on the column 12, the nuts 16 passing between the ribs 36 and 37.

The fasteners 15 are then given a quarter turn. The nuts 16, being of a greater length than the distance between ribs 36 and 37, will lock the column 11 to the column 12. The column 11 is then seated over the stabilizer block 67, the block 67 entering the channel 29 of the column 11. The column 11 is now fixed into position and the fasteners 15 can be drawn tight. As the fasteners 15 are drawn together, the column 11 telescopes onto column 12 and will clamp the panels 13 and 13a between the flanges 24, 33 and 25, 34. One end of the panels 13 and 13a is now in fixed position. The same procedure is repeated at the other end of the panels and continued until the partition is complete.

The insert 14 is now placed in the channel 30 and a similar insert placed in the channel 29 and the assembly 15 is complete.

Disassembly of the partition may be accomplished by reversing the previously described method of assembly.

It can be seen that the structural beam assembly disclosed herein provides a versatile, simple and economical arrangement for partitions. It also provides for a partition which is neat appearing and decorative.

Furthermore, if a panel such as 13 is damaged or it is desirable to replace it with a panel having different characteristics, it is a simple matter to disassemble a pair of structural beam assemblies and replace the existing panel with the new panel.

While a preferred embodiment of this invention has been described, it will be understood that other modifications and improvements may be made thereto. Such of these modifications and improvements as incorporate the principles of this invention are to be considered as included in the hereinafter appended claims unless these claims by their language expressly state otherwise.

We claim:

1. A support structure for partitions comprising:
  - (a) a beam having two separable, generally H-shaped columns;
  - (b) one of said columns having legs secured together proximate to the center portions thereof by a cross tie;
  - (c) the other of said columns having offset legs secured together proximate to the center portions thereof by a cross tie;
  - (d) partition securing flanges laterally extending from the outwardly extending portions of the legs of said column;
  - (e) the inwardly extending portions of the legs of said one column telescoping over the inwardly extending portions of the offset legs of said other column;
  - (f) elongated spaced ribs projecting toward each other from opposite faces of the inwardly extending portions of said offset legs;
  - (g) at least one metallic fastening nut positioned be-

tween said ribs and the cross tie of said other column, the spacing between said ribs being greater than the small dimension of said fastening nut and smaller than the large dimension of said fastening nut, said fastening nut engaging said ribs as an axial stop and also engaging the opposite surfaces of said legs of said other column as a rotational stop;

(h) at least one metallic fastening screw projecting through the cross tie of said one column and through the spacing between said ribs, said fastening screw engaging said fastening nut to hold said columns together; and

(i) insert strips fitting between the outwardly extending portion of the legs of said columns.

2. The support structure for partitions as specified in claim 1 wherein: at least one U-shaped plate is engaged with said partition securing flanges, said plate having keyway means formed in the exposed surface thereof and a partition supporting land formed between said keyway means; and resilient blind stop strips are mounted in said keyway means, said blind stop strips adapted to clamp partitions of various thicknesses as placed on said land.

3. The support structure for partitions as specified in claim 1 wherein, said beam cooperates with an adjustable anchor member having a central portion adapted to be anchored to a floor and having at least a pair of spaced, vertically extending backing members; and stabilizer blocks fastened to said backing members, said stabilizer blocks shaped to slidably engage said beam between the outwardly extending portions of the legs of said columns.
